CONTAINER CAPS AND METHODS FOR
MAKING THEM

Edward J. Towns, Livingston, N.J., assignor to Minnesota Mining and Manufacturing Company, St. Paul, Minn., a corporation of Delaware

Filed Nov. 22, 1957, Ser. No. 698,082

7 Claims. (Cl. 215—46)

This invention relates generally to a cap for sealing a container, such as a bottle, and in one of its more specific aspects to a cap which is adapted to provide an effective original seal for a bottle and which is adapted to be readily reused, subsequent to initial use, to adequately reseal the bottle. This invention also pertains to an improved method for manufacturing resilient and reusable bottle caps.

A primary object of the invention is to provide a reusable bottle cap having improved features of construction and design.

Another object of the invention is to provide a bottle cap which is adapted (a) to be readily applied to a bottle or the like and serve as an effective original seal therefor, (b) to be easily removed from the bottle, as required, and (c) to be readily and quickly reapplied to the bottle to thereby adequately reseal the same.

The invention has for another object the provision of a reusable bottle cap which indicates visually, when in active use, whether it is being used to effect original sealing or resealing of the bottle.

A further object of the invention is to provide a bottle cap of the character indicated that is simple and attractive in design, that is durable in construction, that is reasonable in manufacturing cost and that is capable of performing its intended functions in a satisfactory and trouble-free manner.

To the end that the foregoing objectives may be attained, a bottle cap according to this invention is unitary in construction and is made of a suitable resinous composition which may be thermoplastic and/or thermosetting material which is readily moldable and which has the properties of being flexible, resilient, tearable, and inert and impervious to moisture and common gases. While polyethylene is preferred, it is to be understood that other thermoplastic or thermosetting materials having similar properties and characteristics may be used in place thereof.

The cap comprises a top wall and outer and inner tubular walls depending from the top wall and open at their lower ends. The inner wall is spaced from and substantially coaxial with the outer wall. An annular bead is provided at the lower end of the outer wall and projects inwardly thereof. This bead has a plurality of circumferentially spaced blind recesses that extend upwardly from its lower surface. The recesses extend into the outer wall but terminate inwardly of both the inner and outer surfaces of the outer wall. The recesses may be of any desired form and the parts of the cap defining the recesses constitute weakened areas that are tearable in the course of removing the cap from a bottle by means of a bottle opener or similar device.

The cap is adapted to be readily placed on a bottle and form an effective seal therewith as will be explained further along herein. When the cap is used to provide an original seal for the bottle, the parts are so arranged that the recesses are not visible and the outer wall is continuous and uninterrupted by slits, tears, or the like.

2

At the time the cap is removed from the bottle the outer wall is partially torn in the region of one or two of the recesses. The cap may be reused to reseal the bottle by repositioning it thereon. When the cap is used as a resealer, the tears appearing in the outer wall serve as visible indications that the cap is not an original sealer, but is being used for resealing purposes.

I find that for best results the inner tubular wall of the cap should be preferably somewhat softer and more pliable than the outer tubular wall. Accordingly, it is recommended that different thermoplastic and/or thermoset compositions be used for the outer and inner walls. If desired, the cap may be made of two polyethylene compositions having requisite characteristics, which are molded to obtain a unitary or one-piece cap construction as will be described further along in this description.

The enumerated objects and other objects, together with the advantages of this invention, will be readily understood by persons skilled in the art from the following detailed description taken in conjunction with the accompanying drawings.

In the drawings:

Fig. 1 is a perspective view of a cap constructed in accordance with this invention operatively mounted on a bottle;

Fig. 2 is a central vertical cross sectional view through the cap and bottle assembly shown in Fig. 1;

Fig. 3 is a bottom plan view of the cap shown in Fig. 1;

Fig. 4 is an enlarged fragmentary view of a portion of Fig. 3;

Fig. 5 is an enlarged view of the left hand portion of only the cap of Fig. 2;

Fig. 6 corresponds to Fig. 1 and illustrates the cap in the course of its being removed from the bottle with the aid of a bottle opener;

Fig. 7 also corresponds to Fig. 1 and depicts the appearance of the cap when it is being reused for the purpose of resealing the bottle;

Fig. 8 is an enlarged central vertical cross sectional view through the cap shown in other views and illustrates the parts thereof that are molded from one composition and the parts that are molded from a second composition in accordance with this invention;

Fig. 9 is a view in vertical cross section of an arrangement of molding apparatus for forming certain parts of the cap of this invention;

Fig. 10 is similar to Fig. 9 and illustrates molding apparatus for forming the remaining parts of the cap; and

Fig. 11 is a perspective view of a separating plate.

Reference is now had to the drawings wherein like reference characters denote corresponding parts throughout the several views. There is illustrated in Figs. 1 and 2 the upper portion of a bottle B and a cap C of this invention positioned on and forming a seal with the bottle.

Bottle B is preferably made of glass and may be of any conventional construction and design that is commonly used to store gas-containing liquids, such as ginger ale, carbonated water and the like. The bottle, to the extent that it is illustrated, includes a tubular neck 10 having an inner surface 11 and terminating in a pair of outer annular beads, namely an upper bead 12 and a lower bead 13. These beads merge and define an annular groove 14, as best shown in Fig. 2.

Cap C comprises a circular top wall 15, a depending outer tubular wall or skirt 16 and a depending inner tubular wall or sealing ring 17 that is spaced from and coaxial with the outer wall. Walls 15, 16, and 17 are imperforate. Top wall 15 carries a plurality of radial stiffening ribs 18 that are positioned wholly within inner wall 17. The lower end of wall 16 includes an inwardly

projecting annular bead 19. A plurality of circumferentially spaced blind recesses 20 extend into wall 16 as shown in Figs. 4 and 5, but terminate inwardly of the upper inner surface of bead 19. The parts which define individual recesses 20 constitute weakened regions of the cap. If desired, there may be positioned on the ribs 18 a bottle cap liner (not shown) of any of the types known to the art.

When cap C is originally applied to bottle B, it is heated sufficiently to soften its parts and permit positioning on the bottle as shown in Fig. 2, with inner wall 17 disposed in the bottle and forming intimate contact with bottle surface 11 and bead 19 engaging outer bead 13 of the bottle as shown. This is accomplished without tearing or otherwise breaking through outer wall 16 or bead 19.

Assuming that the bottle contains a carbonated liquid, the fluid pressure within the bottle acts on top wall 15 and inner wall 17 in a manner to obtain an effective seal between the bottle and the cap. The bottle and its contents may now be transported, stored or displayed under normally encountered temperature and pressure conditions without disturbing the seal. The fact that top wall 15 and outer wall 16 are continuous and uninterrupted by tears or other disfigurements serves as a visible indication to a purchaser that the bottle is under its original seal. In other words, the customer is assured that the original seal has not been broken and that the original contents are intact.

The cap may be readily removed from the bottle by means of a conventional bottle opener O (Fig. 6) which includes a handle 21, an upper jaw 22 and a lower jaw 23. The opener is adapted to engage the cap with its upper jaw bearing on top wall 15 and its lower jaw hooked under outer wall 16 and engaging bead 19. The opener is tilted upwardly in the usual manner to pry the cap from the bottle. In the course of such prying, the opener causes partial tearing of outer wall 16 and bead 19 in the regions of recesses 20 that are adjacent jaw 23, as shown in Fig. 6. Typical tear lines resulting from use of the opener are indicated by numeral 24 in Figs. 6 and 7.

Despite the tears resulting from breaking the original seal, the cap may be repeatedly reused to reseal the contents of the bottle or other bottles. Tear lines 24 constitute an indication to a user that the cap is being used for resealing purposes as distinguished from original sealing.

As was mentioned earlier in this description, inner tubular wall 17 is preferably made of a thermoplastic composition that is somewhat softer, more pliable and therefore more flexible than outer tubular wall 16. Fig. 8 illustrates a cap that is formed from two polyethylene compositions to obtain a construction having the indicated properties and characteristics. In Fig. 8, inner wall 17 is first formed from the softer polyethylene composition while outer wall 16, annular bead 19, the top wall 15 and ribs 18 are all made of a stiffer, less pliable polyethylene composition.

Reference is next had to Figs. 9 and 10 which illustrate molding apparatus for forming the cap of Fig. 8. The molding apparatus includes a press comprising a lower platen 25 which carries a bed plate 26. Mounted on the bed plate is a mold 27 having a plurality of grooves, namely an annular top groove 28 corresponding in size and configuration to inner wall 17, a plurality of radial top grooves 29 corresponding in number, size and configuration to ribs 18, and an annular side groove 30 corresponding in size and configuration to bead 19. Mold 27 registers with a hollow outer block 31. An inner block 32 is positioned within the outer block and carries a central tube 33 and a cover plate 34 having a diametrically disposed slot 35 extending entirely across said plate and communicating at its central part with tube 33. With the parts disposed in the relationship as

shown in Fig. 9, the ends of the slot 35 communicate with narrow cylindrical openings 9 which in turn communicate with annular groove 8 in registry with groove 28. A polyethylene or other resinous composition of predetermined desirable properties is injected by the use of pressure and heat through the central opening in the tube 33, into and through the confined slot 35, into and through the pair of narrow cylindrical openings 9 and into the mold space defined by the grooves 8 and 28 to thereby form the annular inner wall 17 together with an annular ring 17a integral therewith and have a pair of space annular beads 17b on the upper face thereof.

Block 31 is adapted to be replaced by a similar block 37 for the purpose of forming top wall part 15, ribs 18, outer wall 16 and bead 19. As shown in Fig. 10, block 37 and mold 27 define a space 38 corresponding in size and configuration to outer wall 16. Block 32 is likewise replaced by a similar block 32a and spaced above the earlier formed portions of the cap, as indicated at 39. This construction permits ready injection of a second polyethylene or other resinous composition 40 (Fig. 8) of the desired characteristics into the mold spaces to form top wall part 15, ribs 18, outer wall 16 together with its bead 19. The composition 40 is in a molten or semi-molten state during molding, whereby fusion occurs between composition 40 and ring 17a so that wall 17 and top wall 15 are bonded together to obtain a unitary cap.

Recesses 20 are preferably formed in the lower end of outer wall 16 after molding is completed and the cap is removed from the molding apparatus. It will be appreciated that the recesses may be formed during the molding procedure, if desired.

From the foregoing, it is believed that construction and advantages of the bottle cap of this invention and the method of making the same will be readily comprehended by persons skilled in the art, without further description. It is to be understood, however, that the invention is not to be limited to the exact details described and shown herein, but is to be accorded the full scope and protection of the appended claims.

I claim:

1. In a frangible cap which is adapted to seal a container, such as a bottle, having an outer bead at its discharge end, a top wall, an outer tubular wall depending from the top wall and open at its lower end, an inner tubular wall depending from the top wall and open at its lower end, said inner wall being spaced from and substantially coaxial with the outer wall, the lower end of the outer wall including an inwardly extending annular bead, said lower end having formed therein a plurality of circumferentially spaced blind recesses that extend upwardly from its lower surface, said cap being adapted to be operatively connected to the bottle with the top wall positioned over and across the discharge end of the bottle, the inner wall disposed in and forming intimate contact with the inner surface of the discharge end of the bottle, the outer wall encircling the bottle outer bead and the annular bead forming continuous intimate contact with the bottle outer bead, the parts of the cap which define the recesses constituting relatively weak regions that are adapted to be torn in the course of prying the cap from the bottle.

2. In a frangible cap which is adapted to seal a container, such as a bottle, having an outer bead at its discharge end, a top wall, an outer tubular wall depending from the top wall and open at its lower end, an inner tubular wall depending from the top wall and open at its lower end, said inner wall being spaced from and substantially coaxial with the outer wall, said top, outer and inner walls being imperforate, the lower end of the outer wall including an inwardly projecting annular bead, said lower end having formed therein a plurality of circumferentially spaced blind recesses that extend upwardly from its lower surface, said cap being adapted

to be operatively connected to the bottle with the top wall positioned over and across the discharge end of the bottle, the inner wall disposed in and forming intimate contact with the inner surface of the discharge end of the bottle, the outer wall encircling the bottle outer bead and the inwardly projecting bead forming continuous intimate contact with the bottle outer bead, the parts of the cap which define the recesses constituting relatively weak regions that are adapted to be torn in the course of prying the cap from the bottle.

3. In a frangible cap which is adapted to seal a container, such as a bottle, having an outer bead at its discharge end, a top wall, an outer tubular wall depending from the top wall and open at its lower end, an inner tubular wall depending from the top wall and open at its lower end, said inner wall being spaced from and substantially coaxial with the outer wall, the lower end of the outer wall including an inwardly projecting annular bead, said lower end having formed therein a plurality of circumferentially spaced blind recesses that extend upwardly from its lower surface, that extend into the outer wall and that terminate inwardly of the outer surface of the outer wall, said cap being adapted to be operatively connected to the bottle with the top wall positioned over and across the discharge end of the bottle, the inner wall disposed in and forming intimate contact with the inner surface of the discharge end of the bottle, the outer wall encircling the bottle outer bead and the inwardly projecting bead forming continuous intimate contact with the bottle outer bead, the parts of the cap which define the recesses constituting relatively weak regions that are adapted to be torn in the course of prying the cap from the bottle.

4. In a frangible cap which is adapted to seal a container, such as a bottle, having an outer bead at its discharge end, a top wall, an outer tubular wall depending from the top wall and open at its lower end, an inner tubular wall depending from the top wall and open at its lower end, said inner wall being spaced from and substantially coaxial with the outer wall, said top, outer and inner walls being imperforate, the lower end of the outer wall including an inwardly projecting annular bead, said lower end having formed therein a plurality of circumferentially spaced blind recesses that extend upwardly from its lower surface, that extend into the outer wall and that terminate inwardly of the outer surface of the outer wall, said cap being adapted to be operatively connected to the bottle with the top wall positioned over and across the discharge end of the bottle, the inner wall disposed in and forming intimate contact with the inner surface of the discharge end of the bottle, the outer wall encircling the bottle outer bead and the annular bead forming continuous intimate contact with the bottle outer bead, the parts of the cap which define the recesses constituting relatively weak regions that are adapted to be torn in the course of prying the cap from the bottle.

5. In a frangible cap which is adapted to seal a container, such as a bottle, having an outer bead at its discharge end, a top wall, an outer tubular wall depending from the top wall and open at its lower end, an inner tubular wall depending from the top wall and open at its lower end, said inner wall being spaced from and substantially coaxial with the outer wall, a plurality of stiffening ribs depending from the top wall and positioned wholly within the inner wall, the lower end of the outer wall including an inwardly extending annular bead, said lower end having formed therein a plurality of circumferentially spaced blind recesses that extend upwardly from its lower surface, said cap being adapted to be

operatively connected to the bottle with the top wall positioned over and across the discharge end of the bottle, the inner wall disposed in and forming intimate contact with the inner surface of the discharge end of the bottle, the outer wall encircling the bottle outer bead and the annular bead forming continuous intimate contact with the bottle outer bead, the parts of the cap which define the recesses constituting relatively weak regions that are adapted to be torn in the course of prying the cap from the bottle.

10 6. In a frangible cap which is adapted to seal a container, such as a bottle, having an outer bead at its discharge end, a top wall, an outer tubular wall depending from the top wall and open at its lower end, an inner tubular wall depending from the top wall and open at its lower end, said inner wall being spaced from and substantially coaxial with the outer wall, said top, outer and inner walls being imperforate, a plurality of stiffening ribs depending from the top wall and positioned wholly within the inner wall, the lower end of the outer wall including an inwardly projecting annular bead, said lower end having formed therein a plurality of circumferentially spaced blind recesses that extend upwardly from its lower surface, that extend into the outer wall and that terminate inwardly of the outer surface of the outer wall, said cap being adapted to be operatively connected to the bottle with the top wall positioned over and across the discharge end of the bottle, the inner wall disposed in and forming intimate contact with the inner surface of the discharge end of the bottle, the outer wall encircling the bottle outer bead and the annular bead forming continuous intimate contact with the bottle outer bead, the parts of the cap which define the recesses constituting relatively weak regions that are adapted to be torn in the course of prying the cap from the bottle.

15 7. In a one-piece thermoplastic, flexible, frangible cap which is adapted to seal a container, such as a bottle, having an outer bead at its discharge end, a top wall, an outer tubular wall depending from the top wall and open at its lower end, an inner tubular wall depending from the top wall and open at its lower end, said inner wall comprising a material that is more pliable than the material of the outer wall and being spaced from and substantially coaxial with the outer wall, said top, outer and inner walls being imperforate, a plurality of stiffening ribs, depending from the top wall and positioned wholly within the inner wall, the lower end of the outer wall including an inwardly projecting annular bead, said lower end having formed therein a plurality of circumferentially spaced blind recesses that extend upwardly from its lower surface, that extend into the outer wall and that terminate inwardly of the outer surface of the outer wall, said cap being adapted to be operatively connected to the bottle with the top wall positioned over and across the discharge end of the bottle, the inner wall disposed in and forming intimate contact with the inner surface of the discharge end of the bottle, the outer wall encircling the bottle outer bead and the annular bead forming continuous intimate contact with the bottle outer bead, the parts of the cap which define the recesses constituting relatively weak regions that are adapted to be torn in the course of prying the cap from the bottle.
